UNITED STATES PATENT OFFICE

JOHN H. HICKEY, OF SAN FRANCISCO, CALIFORNIA, ASSIGNOR TO HICKEY FUSE & MANUFACTURING COMPANY, OF SAN FRANCISCO, CALIFORNIA, A CORPORATION OF CALIFORNIA

REFILLABLE FUSE

Application filed July 7, 1928. Serial No. 291,039.

REISSUED

My invention relates to improvements in refillable fuses wherein a fusible element is mounted within a casing between terminal members detachably secured upon the ends of said casing and provided with improved means for alining the terminals and clamping said members in sealing relation to the ends of the casing.

The primary object of my present invention is to provide a refillable fuse of simplified and improved construction.

Another object is to provide an improved fuse wherein the terminals are readily removable to receive a new fusible element and which will facilitate the reassembly of the fuse.

A further object is to provide an improved construction which will effectually seal the ends of the fuse casing.

Another object is to provide an improved device which is simple and positive in its action and which will permit the fuse to be refilled repeatedly.

A still further object is to provide an improved construction which can be manufactured economically and which is durable and efficient in service.

I accomplish these and other objects by means of the improved device disclosed in the drawings forming a part of the present application wherein like characters of reference are used to designate similar parts throughout the specification and drawings and in which—

Fig. 1 is a longitudinal section of my improved refillable fuse;

Fig. 2 is a side elevation, partly in longitudinal section of the fuse, the view being shown in a position at right angles to the position shown in Fig. 1;

Fig. 3 is an end elevation of the fuse;

Fig. 4 is a plan view of the clamping member;

Fig. 5 is a plan view of the alining plate;

Fig. 6 is a plan view of a modified form wherein the clamping plate is secured to the alining plate; and

Fig. 7 is a transverse section of the modified form, taken upon the line 7—7 of Fig. 6 in the direction indicated.

Referring to the drawings, the numeral 1 is used to designate a cylindrical casing threaded at both ends, as at 2. Terminal members 3 and 4 are mounted within the ends of the casing, said terminals consisting of annular flange portions having inwardly extending lugs 3' and 4' and outwardly extending blade portions 3'' and 4'' respectively.

The terminal member 3 is provided with an annular shoulder 6 arranged to seat upon the end of the casing 1. A lug 7 is formed upon the shoulder to engage a recess formed in the end of the casing to define the normal operative position of the terminal. A collar 8 is threaded onto the end of the casing 1 and provided with an inwardly disposed flange 9 arranged to seat against the terminal 3 to hold the terminal member seated in sealing relation to the end of the casing.

The terminal member 4 is movable through the casing 1, the flange portion being received within the end of the casing. An alining plate 11 having an annular shoulder 12 is arranged to seat upon the end of the casing 1 adjacent the terminal 4, a lug 13 being formed upon the shoulder 12 to engage a recess formed upon the end of the casing to aline the terminal in respect to the opposite terminal 3. The plate 11 is provided with a slot 14 arranged to slidably receive the outwardly extending blade 4'' whereby the plate 11 may be moved into proximate relation to the flange portion of the terminal 4.

A clamping member 16 having a slot 17 arranged to slidably engage the blade 4'' is mounted in proximate relation to the alining plate 11. Arcuate recesses 18 are formed in the center of the member 16 to permit the member 16 to be rotated upon a reduced portion of the blade 4'' formed by notches 19 formed in the sides of said blade portion. Inclined surfaces 21 are formed upon the outer side of the member 16 to be received within the notches 19, the outer sides of the notches being inclined to correspond to the surfaces 21. The member 16 may fit loosely onto the outer end of the terminal 4 and against the alining plate 11, or if desired, pins 22 may be arranged to extend

through arcuate slots 23 formed in the member 16, said pins being secured upon the alining plate 11 and being provided with heads arranged to engage the outer surface of the member 16 whereby the clamping member 5 may be held in engagement with the plate 11 so that the two members may be applied and removed together.

A collar 24 is threaded onto the end of the 10 casing 1 and provided with an inwardly disposed flange 26 arranged to seat upon the outer edge of the member 16 whereby the member 16 may be held firmly seated upon the plate 11 and said plate 11 in turn held 15 firmly seated upon the end of the casing.

A suitable fusible element 27 is secured between the inwardly extending lugs 3' and 4' by suitable securing members 28 in the well known manner.

20 In operation, the fuse is assembled by securing the fusible element 27 between the lugs 3' and 4' and then inserting the terminal 4 and the fusible element through the casing until the terminal 3 is seated upon the 25 end of the casing. The collar 8 is then threaded onto the end of the casing to clamp the terminal firmly against the end of the casing, the collar being tightened to effectually seal the end of the casing and prevent the 30 escape of gas around the ends of the terminal. The lug 7 defines the position of the terminal relative to the end of the casing.

After the collar 8 has been applied, the 35 alining plate 11 is moved onto the outwardly extending blade portion of the terminal 4 and is seated upon the adjacent end of the casing 1, the lug 13 being moved to engage its recess in the end of the casing to aline the terminal 4 with respect to the opposite terminal 3. The 40 clamping member 17, which may be either applied separately or linked to the plate 11 by the pins 22 as above described, is then turned to cause the inclined surfaces 21 to enter the notches 19. As the clamping member 17 is 45 turned, the inclined surfaces act as wedges operating to press the plate 11 and the terminal 4 tightly together. The collar 24 is then applied and tightened to press the plate 11 against the end of the casing. The clamping 50 member 17 insures a close contact between the plate 11 and the adjacent surfaces of the terminal 4 and the member 17, and the collar 24 effectually secures and seals the closure across the end of the casing.

55 As thus assembled, the fuse is used in the ordinary manner. When the fusible element 27 is to be replaced, the fuse is taken apart by removing the collars 8 and 24, and a new fusible element applied as above described 60 and the fuse reassembled for further use. The clamping member insures a gas-tight closure, and, being positioned upon the outer side of the terminal and alining plate, is unaffected by gases or metal projected from the 65 fusible element when blown.

The specific details of construction may of course be modified in numerous ways without departing from the spirit of my invention, and I therefore desire to avail myself of all modifications which may fall within the scope of the appended claims. 70

Having thus described my invention what I claim as new and desire to secure by Letters Patent is—

1. A refillable fuse comprising a casing; 75 terminal members arranged to engage the ends of the casing; a fusible element connected between the terminal members; a collar detachably securing one of the terminal members upon the casing; clamping means detachably clamped upon the opposite terminal member and seating upon the adjacent end of the casing; and a collar detachably securing the clamping means upon the end of the casing. 80

2. A refillable fuse comprising a casing; 85 terminal members arranged to engage the ends of the casing; a fusible element connected between the terminal members; a collar detachably securing one of the terminal members upon the casing; a plate engaging the opposite terminal member and seating upon the adjacent end of the casing; clamping means rotatably mounted in proximate relation to the plate and having means for 90 detachably clamping said plate in engagement with the terminal member; and a collar detachably securing the plate and clamping means upon the end of the casing. 95

3. A refillable fuse comprising a casing; 100 terminal members arranged to engage the ends of the casing; a fusible element connected between the terminal members; a collar detachably securing one of the terminal members upon the casing; an alining plate 105 engaging the opposite terminal member and the adjacent end of the casing; a clamping member mounted in engagement with the alining plate and rotatably movable relative thereto to engage notches formed in the terminal member for clamping the terminal and the plate together; and a collar engaging the end of the casing and detachably securing the plate and clamping member upon the end of said casing. 110 115

4. A refillable fuse comprising a casing; 120 terminal members arranged to engage the ends of the casing; a fusible element connected between the terminal members; a cap detachably securing one of the terminal members upon the casing; an alining plate engaging the opposite terminal member and the adjacent end of the casing; a clamping member mounted in engagement with the alining plate and provided with inclined surfaces arranged to engage notches formed in the terminal member to clamp the terminal and plate together; and a collar engaging the 125 end of the casing and detachably securing the 130

terminal and alining plate upon the end of the casing.

5. A refillable fuse comprising a casing; terminal members arranged to engage the ends of the casing; a fusible element connected between the terminal members; a collar detachably securing one of the terminal members upon the casing; an alining plate slotted to engage the opposite terminal and arranged to seat upon said terminal and the adjacent end of the casing; a clamping plate mounted in proximate relation to the alining plate and rotatably movable relative thereto, said clamping plate having inclined surfaces arranged to engage notches formed in the terminal to clamp the terminal and plate together; and a collar engaging the end of the casing and detachably securing the terminal and alining plate upon the end of the casing.

6. A refillable fuse comprising a casing; terminal members arranged to engage the ends of the casing, said members each comprising an annular flange having inwardly extending lugs and outwardly extending blade portions; a fusible element connected between the inwardly extending lugs; a collar detachably securing the flange portion of one terminal member against one end of the casing; an alining plate slotted to fit over the blade of the opposite terminal member and arranged to seat upon the adjacent end of the casing; clamping means rotatably mounted in connection with the alining plate and movable to clamp said plate and the terminal flange together; and a collar detachably securing the alining plate and clamping means against the end of the casing.

7. A refillable fuse comprising a casing; terminal members arranged to engage the ends of the casing, said members each comprising an annular flange portion having inwardly extending lugs and outwardly extending blade portions; a fusible element connected between the inwardly extending lugs; a collar detachably securing the flange portion of one terminal member seated against one end of the casing; an alining plate slotted to fit over the blade of the opposite terminal and arranged to seat upon the adjacent end of the casing; a clamping plate rotatably mounted upon said blade in proximate relation to the alining plate, said clamping plate having inclined surfaces arranged to engage notches formed in the blade for clamping the terminal member and the alining plate together; and a collar detachably securing the alining plate seated against the adjacent end of the casing.

8. In a refillable fuse having a casing and terminal members detachably secured upon the ends of said casing, an alining plate arranged to seat upon one end of the casing, said plate being slotted to receive a terminal member; and a clamping plate mounted in

proximate relation to the alining plate, said clamping plate being rotatably movable relative to the terminal member and alining plate and having inclined surfaces arranged to engage notches formed in the terminal member for detachably clamping the terminal member and the alining plate together.

9. In a refillable fuse having a casing and terminal members detachably secured upon the ends of said casing, an alining plate arranged to detachably engage a terminal member and to seat upon one end of the casing; and a clamping plate rotatably mounted upon the terminal member in proximate relation to the alining plate and provided with inclined surfaces engaging notches formed in the terminal member for clamping the terminal member and alining plate together.

10. In a refillable fuse having a casing, a terminal member having a flange fitted within an end of the casing; an alining plate seated upon the end of the casing, said plate being slotted to slidably engage the terminal member; and a clamping member mounted in proximate relation to the outer surface of the alining plate, said clamping member being rotatably movable relative to the plate and terminal member and having means movable into clamping engagement with notches formed in said terminal member to clamp said member and the alining plate together.

11. In a refillable fuse having a casing, a terminal member having a flange fitted within an end of the casing; an alining plate seated upon the end of the casing, said plate being slotted to slidably engage the terminal member; and a clamping member mounted upon the terminal member in proximate relation to the outer surface of the alining plate, said clamping member being rotatably movable and having inclined surfaces arranged to engage notches formed in the terminal member to clamp said member and the alining plate together.

12. In a refillable fuse having a casing, terminal members mounted within the ends of the casing, one of said members being arranged to seat upon the end of the casing and having a lug engaging a recess in the end of the casing to aline the member; an alining plate slidably engaging the opposite terminal and arranged to seat upon the adjacent end of the casing, said alining plate having a slot arranged to receive the outer end of the terminal member and having a lug arranged to engage a recess formed in the end of the casing to aline said plate and terminal with the opposite terminal; and a clamping plate slidably and rotatably engaging the outer end of the terminal member and provided with inclined surfaces arranged to engage notches formed in said terminal member adjacent the alining plate for clamping said plate and the terminal member together.

13. In a renewable fuse, the combination

of a tubular fuse body, a terminal blade arranged to extend through the end of said body, an abutment on said terminal blade extending outwardly from the sides of the blade, the blade being provided with a restricted neck outside of said abutment, a slotted washer arranged to be slipped down over the terminal blade to rest against the abutment and close the end of the fuse body, a sealing disk having a central aperture enlarged at diametrically opposite points to permit the disk when turned into one position to be slipped down over the blade and rest on the washer, said disk being then rotated relative to the washer to clasp the restricted neck of the blade, and seal the ends of the slot of the washer, and means separate from the sealing washer for clamping the disk against the washer and the washer against the end of the fuse body.

14. In a renewable fuse, the combination of a tubular fuse body, a terminal blade arranged to extend through the end of said body, an abutment on said terminal blade extending outwardly from the sides of the blade, the blade being provided with a restricted neck outside of said abutment, a slotted washer arranged to be slipped down over the terminal blade to rest against the abutment and close the end of the fuse body, a sealing disk having a central aperture enlarged at diametrically opposite points to permit the disk when turned into one position to be slipped down over the blade and rest on the washer, said disk being then rotated relative to the washer to clasp the restricted neck of the blade and seal the ends of the slot of the washer, and an annular cap arranged to be screwed on the end of the fuse body to clamp the disk to the washer and the washer to the end of the fuse body.

In witness whereof, I hereunto set my signature.

JOHN H. HICKEY.
